DESIGN FOR A RANGE BOILER

Richard S. Rheem, Oakland, Calif., assignor to
Rheem Manufacturing Company, Richmond,
Calif., a corporation of California

Application May 7, 1935, Serial No. 56,714

Term of patent 3½ years

To all whom it may concern:

Be it known that I, Richard S. Rheem, a citizen
of the United States and a resident of Oakland,
county of Alameda, and State of California, have
invented a new, original, and ornamental Design
for a Range Boiler, of which the following is a
specification, reference being had to the accom-
panying drawing, forming part thereof.

Figure 1 is a perspective view of the range

boiler of my invention, as viewed from the front
and top.

Figure 2 is a view similar to Figure 1, showing
the range boiler as viewed from the front and
bottom.

I claim:

The ornamental design for a range boiler sub-
stantially as shown.

RICHARD S. RHEEM.
